UNITED STATES PATENT OFFICE.

WALTER S. LEVIN, OF SAN FRANCISCO, CALIFORNIA, ASSIGNOR TO THE NATIONAL SAFETY APPLIANCE COMPANY, OF SAN FRANCISCO, CALIFORNIA, A CORPORATION OF CALIFORNIA.

RELAY.

1,305,381.

Specification of Letters Patent. Patented June 3, 1919.

Application filed May 5, 1915. Serial No. 25,895.

To all whom it may concern:

Be it known that I, WALTER S. LEVIN, a citizen of the United States, and a resident of San Francisco, county of San Francisco, 5 State of California, have invented certain new and useful Improvements in Relays, of which the following is a description.

This invention relates to relays and to that class thereof which is especially useful 10 in line circuits and train signaling and stopping apparatus. One of these relays is to be used at every signal or automatic stop location and is supplied with current through the necessary line wires connected 15 with a proper battery through the contacts of a track relay which in turn is connected, through the rails, with a battery at the other end of a neighboring block—the presence of a train in this block shunting the 20 current of the track relay thus causing it to drop its armature and open the circuit of the line relay which in turn drops its armature thus setting the proper caution and danger signals. One of the objects 25 of the present invention is to make the use of the back contact, which in all previous patterns of relays is held closed only by the weight of the armature, just as secure as the front contact normally used and this object 30 has been obtained by the construction of the present invention which makes the back contacts just as secure as, or more so than, the front contacts of relays heretofore commonly used. Other objects will appear from 35 the hereinafter description.

The invention will be understood by one skilled in the art from the following description taken in connection with the accompanying drawings wherein the same reference character indicates the same part in 40 the several views.

Referring to the drawings:

Figure 1 is a cross sectional view, partly in elevation, illustrating one embodiment 45 of the invention.

Fig. 2 is a horizontal section on staggered line 2—2 of Fig. 1.

Fig. 3 is a cross sectional view on line 3—3 of Fig. 1.

Fig. 4 is a perspective view showing diagrammatically a simple embodiment of the 50 invention.

On the drawing the part marked 10 represents a casing, to the cover 11 of which 55 are secured the several parts of the relay.

A represents a pair of electromagnets the windings of which are connected by wires R through a contact make and break device S to a battery T. These magnets are provided with L-shaped pole pieces B which 60 may be formed integral with the cores A'. The two members are marked respectively, b¹, b², the latter being a projection on the ordinary form of pole piece b¹. b³ represents screws which pass through the pole 65 pieces and are screwed into the cover 11. C is an armature to which are secured the arms c¹ and by which the armature is pivoted at c² to lugs 12 on the cover 11. H is another armature to which are secured 70 the arms h¹ by which the said armature is pivoted at h² to lugs 13 projecting from the cover of the casing. The armatures are so constructed and arranged that they coact respectively with the members b¹ and b² of the 75 pole pieces B, and the movement of one is entirely free and independent of the movement of the other. D represents pieces or blocks of insulating material secured to the armature C and to which are secured the 80 contact arms F and which insulate the said arms from the armatures. D' is another piece of insulating material secured to the armature H and to which the contact arm E is secured and by which said arm is insulated from the said armature H. G is an 85 electromagnet supported by the L-shaped brackets 14 secured to the cover of the casing. The brackets 14 afford respectively suitable supports for a block of insulating 90 material 15 to carry suitable terminals or binding posts 16 to which the wiring shown diagrammatically in Fig. 4 may in practice be connected. This magnet is provided with upwardly extending pole pieces N which 95 are so arranged that they attract the armature C but have no influence on the armature H so as to effect its practical operation. In other words, no appreciable influence is exerted upon the armature H. In 100 the diagrammatic view of Fig. 4, for the purpose of clearer illustration, this magnet is shown elongated and the pole pieces near the end of the armature C, but in practice the construction and arrangement is that 105 shown in the other figures of the drawing. The letters I represent the front contacts respectively for each of the arms F, and I' the front contacts for the arm E. These arms rest normally against these contacts 110

when the said arms are held up by the magnets A. The letters K represent the back contacts respectively for each of the arms F, and K' the back contact for the arm E and against which the said arms rest when they have been released from the magnets upon the opening of the said magnet circuit. M represents terminals or binding posts connected to the contact arms F by flexible connections L, and M' is another terminal or binding post connected to the arm E by a flexible connection L', the said terminals being used to connect suitable wiring. O represents circuit wires, one section of which connects the magnet G to the back contact K', and the other section of which connects said magnet with the terminal or post M', through the battery P. The contact arm E is used only for controlling the circuit of the electromagnet G, while the arms F are used for controlling external circuits, any number of which may be used, only two being shown for illustrating the action of the relay.

The operation of the invention may be briefly stated as follows: When the magnets A are energized by operating the contact making device S, the armatures C and H are drawn in contact with the pole pieces B and the contact arms F and E are held firmly against the front contacts I and I'. When the circuit of the magnet is broken by opening the contact device S, the magnets A are deenergized, the armatures C and H are released from the pole pieces and drop away therefrom and the respective contact arms F and E carried thereby come into engagement with the back contacts K and K' respectively. The closing of the contact between E and K' causes the magnet G to be energized, whereupon the armature C is attracted by the pole pieces N and the contact arms F connected to the armature C are firmly held against the back contacts K. When the magnets A are again energized, the armature C will not immediately be raised, as it is held down by the magnet G, but the pole extension b² attracts the armature H which raises the arm E out of engagement with the contact K' to open the circuit O, whereupon the magnet G is deenergized and the armature C is released from the poles N of the magnets A, whereupon the arms carried thereby are raised and held against the front contacts I. If desired, the ends of all of the contact arms may be provided with contact fingers e¹, e², and f¹, f², as shown in Figs. 1 and 3, which may be made of spring metal whereby a yielding engagement with the front and back contacts may be secured.

As many changes could be made in the above construction and many apparently widely different embodiments of the invention could be made without departing from

the scope thereof, I intend that all matter contained in the above description or shown in the accompanying drawings shall be interpreted as illustrative and not in a limiting sense.

I desire it also to be understood that modifications of the structure may be made which fall within the scope of the claims.

Having now described my invention, what I claim as new and desire to secure by Letters Patent is:

1. In a device of the class described, an electro-magnet having a pole piece with a projection connected thereto, an armature to be attracted by the pole piece, another armature to be separately and independently attracted by the said projection, a contact arm connected to each armature, front and rear contacts against which the arms contact in one position or the other, a second magnet, and a circuit connecting said second magnet and the arm connected to the second mentioned armature, said circuit being opened when the first magnet is energized and closed when the said first magnet is deenergized, whereby the second magnet is energized and holds the arm connected to the first armature in contact with the back contact.

2. In a device of the class described, an electromagnet, an L-shaped pole piece therefor, an armature attracted by one member of the said pole piece, another armature attracted by the other member thereof independently of the first armature, contact arms carried by the first mentioned armature, another contact arm carried by the second armature, front and back contacts for each arm, another electromagnet to attract the first mentioned armature and hold the first mentioned arms in contact with the back contacts, the second magnet being in circuit with the arm carried by the second armature and the back contact thereof and energized when the first mentioned magnet is deenergized.

3. In a device of the class described, an electromagnet, a pole piece therefor, said pole piece consisting of a main member and a second member, a hinged armature adapted to be attracted by the main member of the said pole piece when the magnet is energized, a second hinged armature adapted to be attracted by the second member of the pole piece independently of the first armature when the magnet is energized, contact arms connected to and insulated from the first mentioned armature, an arm connected to and insulated from the second mentioned armature, front and back contacts for each arm, a second magnet having pole pieces adjacent to and adapted to attract the first mentioned armature, said magnet being in circuit with the last mentioned arm and the back contact thereof, whereby upon the deenergizing of the first mentioned magnet

- the second magnet will be energized through the last mentioned arm and its back contact and will hold the arms carried by the first mentioned armature against the back 5 contacts thereof, and upon the first mentioned magnet being energized the second mentioned arm will be attracted by one member of the pole pieces independently of the first armature and break the circuit of 10 the second magnet, whereupon the first mentioned armature will be attracted by the pole piece and the first mentioned arms will be held in engagement with the front contacts.
4. In a device of the class described, an 15 electro-magnet having a core provided with an L-shaped pole piece, the separate arms of said L-shaped pole piece adapted to independently attract separate armatures, and armatures therefor, each armature coöperating respectively with a separate arm of said L-shaped pole piece.
5. In a device of the class described, a support, an electromagnet secured thereto, a 20 second electromagnet secured to the said support pole pieces for each magnet secured adjacent to each other, nested armatures secured to the support and coöperating re-
- spectively with separate portions of the pole piece of the first mentioned magnet, one of said armatures also coöperating with the 30 pole piece of the said second magnet, fixed contacts and contact arms insulatively connected with the respective armatures.
6. In a device of the class described, a support, an electromagnet secured thereto, 35 a second electromagnet also secured to the said support, a stepped pole piece for the first mentioned magnet pole piece for the second magnet, nested armatures pivotally secured to the support and coöperating 40 respectively with the separate portions of said stepped pole piece, one of said armatures also coöperating with the pole piece of said second magnet, fixed contacts and contact 45 arms insulatively connected with the respective armatures.

In witness whereof, I have hereunto set my hand at San Francisco, county of San Francisco, State of California, this 26th day of April, 1915.

WALTER S. LEVIN.

In presence of—
GEORGE C. FAULKNER,
GOLDAH CHARMAK.
